HEEL-ATTACHING MACHINE

Thomas Aubrey Kestell and William Roderick
Barclay, Leicester, England, assignors to United
Shoe Machinery Corporation, Flemington,
N. J., a corporation of New Jersey

Application January 8, 1940, Serial No. 312,866
In Great Britain February 3, 1939

29 Claims. (Cl. 1—32)

The present invention is concerned with improvements in machines for attaching heels to shoes. It is more particularly concerned with machines having means for positioning accurately a shoe in relation to a heel for its attachment, means for pressing together a lasted shoe and a heel while heel-attaching fastenings are being driven, and a treadle for actuating the shoe-positioning means, the pressing means and also for tripping a clutch to start the machine into power-operation. While such machines have proved able to perform their shoe-positioning and heel-attaching operations satisfactorily, it has been noticed that, owing to the treadle being depended upon to actuate the shoe-positioning means as well as the shoe-pressing means and the clutch, the movement of said treadle by an operator calls for the expenditure of appreciably more energy than when the machine lacks such control of the shoe-positioning means. Consequently, due to fatigue of the operator, the output of the machine is likely to be lessened.

It is one of the various objects of the present invention, in a machine of the above-mentioned type, to substantially lessen the effort required by the operator in actuating the shoe-positioning means and the work-pressing means and in starting the operation of the machine. This may be accomplished by providing power means for actuating at least the shoe-positioning means. Means made effective under the power of the machine is therefore utilized, for causing the shoe-positioning means to become operative during an early portion of the depression of a treadle or other starting member of the machine, which also controls the work-pressing means. The shoe-positioning means of the illustrative embodiment of the invention may comprise a band-clamp having movable arms for engaging the back and sides of the counter-portion of a shoe-upper. It is arranged to be acted on by a spring which tends normally to cause the arms of the clamp to be moved towards each other to engage a shoe. Latching means is provided for holding the arms open against the resistance of the spring, and there are connections from the starting member of the machine which cause the latching means to be moved to free the band-clamp to receive the action of the spring. Further means, including a stopping member of the machine, is provided for moving the latching means into latching position near the end of the power-cycle of the machine, for freeing the shoe from the band-clamp and for loading the spring for the succeeding op-

eration. The necessary movement of the work-pressing means and the starting of the machine are effected by continued depression of the treadle after the closing of the band-clamp on the work.

5 In addition to the attachment of a heel to a shoe, the machine of this invention may be used to spank a top-lift on such an attached heel before the shoe is removed from the machine. For this purpose, a second power-cycle of the machine 10 is needed without releasing the shoe from the band-clamp. The invention therefore has means, arranged for movement by the operator, for preventing the latching means from releasing the shoe from the band-clamp after the first power- 15 cycle of the machine, during which cycle a heel is attached to a shoe, and for allowing it to become operative after the top-lift has been spanked onto the heel during the second power-cycle of the machine.

20 The invention further has as an object the provision of means whereby the band-clamp may be adjusted with relation to a shoe which it is to locate; and means by which said band-clamp may be retained temporarily in an elevated position 25 to facilitate the introduction of the work and conveniently released, either directly by the operator or as an incident to movement of the work-supporting jack. Further, means are preferably provided for variably limiting the descent of the 30 released band-clamp and for cushioning it in its arrested travel.

The invention will now be more fully described with reference to the accompanying drawings, in which

35 Fig. 1 is a broken side elevation of the upper part of the illustrative machine, some elements being omitted;

Fig. 2, an enlarged view, corresponding to Fig. 1, 40 of certain parts more closely associated with the jack-post;

Fig. 3, a like view of other parts seen in Fig. 1 for controlling the closing of the band-clamp;

Fig. 4, a plan view of the band-actuating mechanism;

45 Fig. 5, a view similar to Fig. 4, with parts in section;

Fig. 6, a front elevation of said band-actuating mechanism;

50 Fig. 7, a section along the line VII—VII of Fig. 4; and

Fig. 8, a broken side elevation of the lower part of the machine.

The illustrative machine is similar in many respects to that described in Letters Patent of the

United States No. 1,195,134, Gouldbourn, August 15, 1916, but modified as in Letters Patent of the United States No. 2,085,851, Gouldbourn et al., and No. 2,085,852, Gouldbourn, July 6, 1937. As shown in the accompanying drawings, there is provided upon a frame F a support 1, in which operates fastening-inserting means or drivers 2, and means consisting of a swing-plate 209 for positioning a heel and top-lift in relation to the driving means. Preliminary pressure may be applied to the work and clutch mechanism tripped to initiate power-operation of the machine, through a treadle 4 depressed by the operator. Movement of a lever 6, under the power of the machine, throws out the clutch mechanism to stop the operation upon the completion of a cycle. There is also a band-clamp 3 arranged to engage the back and sides of the counter-portion of the upper of a shoe and to enter the crease. This band-clamp is similar to that described in Letters Patent of the United States No. 2,162,824, Pratt et al., June 20, 1939, and comprises a thin flexible metal U-shaped band 5 having secured to the free ends of its opposite arms plates 7. Rising from the plates are pins 9 which pass through slots formed in the outer ends of band-clamp-actuating arms 11. To the rear of the band, near its lower edge, a block 13 is attached (Fig. 7), this having a pin 15 extending rearwardly from it. The pin is held by a spring-pressed plunger 21 on a bracket 17, secured to a slide 19, arranged as described below.

For mounting the band-clamp so that it may be variously adjusted, there is secured to the machine-column a fixture 25, and guided for vertical movement upon this fixture is a slideable bracket 27. Ball-bearings 29 (Figs. 4 and 5) may be interposed between the fixture and the bracket to permit easy movement of the latter. The bracket 27 has extending forwardly from it a shelf 30 (Fig. 7) with rack-teeth formed on its upper face. Meshing with these rack-teeth is a pinion 31 rotatably mounted on a supporting member 33 for the band-clamp-slide 19, which supporting member is dovetailed on the shelf 30. The pinion 31 is mounted on a transversely-extending shaft 35 journaled in the supporting member 33, and keyed on the outer end of this shaft is a handle 37. By rotating the handle the pinion is caused to travel along the rack-teeth on the shelf 30, so that the supporting member 33 will be caused to move forwardly and rearwardly of the machine. Means is provided for holding the supporting member 33 locked in adjusted position; this means comprises a small block 39 (Fig. 6) positioned in a recess in the member 33 and having an inclined face lying close to a complementally inclined face of the shelf 30. Threaded into the block 39 is the lower end of a spindle 41 rotatable in an upwardly projecting boss 43 on the member 33. The spindle has a shoulder 45, which is arranged to engage the upper face of the recess in which the block 39 is positioned. By rotation of the spindle by a handle 47 secured on it and resting upon the top of the boss, the block can be raised or lowered. When the block is thus lowered, its inclined edge is forced against that of the shelf 30, and prevents movement of the supporting member 33 upon said shelf. The supporting member has a transversely extending guideway 49 (Fig. 7), and movably mounted in this guideway is the slide 19. Passing upwardly through a vertical bore in the slide is a sleeve 51 integral with one of the band-clamp-operating arms 11

and in the sleeve is mounted a stud 53 formed integrally with the other of the band-clamp-operating arms 11. By moving the supporting member 33 forwardly or rearwardly of the machine, as just described, the slide 19, and therefore the band-clamp, will be correspondingly moved so that shoes of different sizes may be accommodated in the machine.

For adjusting the band-clamp laterally of the machine, there is provided a lever 55 pivoted on the sleeve 51. The lever has a rearwardly extending lug 57 (Figs. 4 and 7), to which is attached one end of a link 59 secured at its other end to the supporting member 33. By swinging the lever 55 about the sleeve, since its lug is prevented from transverse movement by reason of its connection to the member 33, the sleeve 51, and hence the band-clamp, will be moved along the ways 49, transversely of the machine. For maintaining the transverse adjustment of the band-clamp, the lever 55 is provided with a pair of stop-screws 61, 61 threaded through the lever at opposite sides of the sleeve and arranged to abut against stops 63 (Figs. 1 and 7) on the supporting member 33. The stop-screws may be so adjusted that no transverse movement of the lever, and hence of the band-clamp, can take place. Consequently, they may be made use of to hold the band-clamp in the desired position relatively to the heel-presenting device. On the other hand, it may be desired that a heel be attached to a shoe in such a manner that it is not located centrally with respect to the heel-end of said shoe, but has its longitudinal center-line offset from the longitudinal center-line of the heel-end of the shoe-bottom toward the outer side. In this case, the stop-screws may be so adjusted that the band-clamp may be moved into either of two positions determined by engagement of said stop-screws with their corresponding stops 63. By this means, the band-clamp may be adjusted quickly to adapt the machine for use on right or left shoes by manipulation of the lever 55.

To provide clearance for the presentation of a heel to the machine and to enable easy positioning of the counter-portion of a shoe in the band-clamp, means is provided for raising said band-clamp, so it is spaced well above the support 1, and for holding it in such position until just before the machine is started into power-operation. For this purpose, there is on the vertically slideable bracket 27 a cam-piece 65, this being so positioned upon the bracket that it will be engaged by a roll carried by the well-known oscillatory nail-loading device, which I have not illustrated. When this device, with its load of nails, is swung into position over the support 1, the roll engages the cam-piece 65 and lifts the bracket 27 and the band-clamp.

For holding the band-clamp in its raised relation while a heel and a shoe are being positioned in the machine, there is pivotally mounted on the bracket 27 a catch 67 (Figs. 1, 2 and 4) in the form of a bell-crank-lever, and co-operating with this catch is a latch 69. The latch is pivoted on the fixture 25 and a spring 71 (Fig. 2) tends to move a projection on its lower end into contact with the catch. When the latch 69 is released, as hereinafter described, the slideable bracket 27 will descend. In order to determine the extent of downward movement, so that the band-clamp will be positioned correctly, there is threaded through a block 73 trunnioned at the top of the bracket the lower end of a link 75. The upper

end of the link is threaded in a second block 76 trunnioned in the end of one arm of a bell-crank-lever 77 fulcrumed on a plate 79. This plate terminates the pressure-plunger 87 of the machine, and has movable upon it, fore and aft of the machine, a slide 95 on which is pivoted at 93 a jack-post 91 (Fig. 2). The other arm of the bell-crank-lever constitutes movement-limiting means for the bracket 27, it being arranged to strike against a boss 81 on the plate 79 upon disengagement of the latch 69. To prevent the bracket from moving down too quickly and causing an undue shock by the striking of the stop-arm of the lever 77 against the boss 81, there is provided a light torsion-spring 83, surrounding the fulcrum of the lever, for counterbalancing the weight of the bracket and the supported parts. The link 75 has right and left screw-threads on its opposite ends, so that by rotating the link the slidable bracket, and with it the band-clamp, may be adjusted up or down relatively to the support 1 to cause it to occupy the desired position for supporting a shoe in the machine. For releasing the catch 67 from the latch 69 to allow the bracket 27 to move down, the catch has secured to it one end of a link 85 (Figs. 4 and 6). At the opposite end, the link is coupled to a handle 87 pivoted on the lever 65. By depression of the handle 87 the catch 67 is caused to move about its pivot out of engagement with the latching-member 69.

The jack-post 91 is provided with a member 89 for engaging the crown or top of a last, it being mounted for movement laterally of the post and also for tipping movement about an axis extending laterally of the machine. The post is provided with a rearwardly extending arm 99 carrying at its rear end a roll 101 (Fig. 2) entering an L-shaped slot 103 in the plate 79. The slot has a straight horizontal portion and at its front end a portion curved downwardly about the axis of the pivot 93. Normally, the roll is at the rear end of the horizontal portion of the slot, so that the post 91 extends vertically. When a shoe, as contrasted with a boot, is being operated on, the post is always maintained in this vertical position, because sufficient clearance exists for the presentation of a shoe to the band-clamp. If, however, a boot is to be applied to the post, it will be necessary to move the slide 95, with the post and the roll forward, and then to swing the post forward as the roll enters the curved portion of the slot. To relieve the operator of the necessity of actuating the handle 87 to release the bracket 27 from the latch 69, so it may move down to carry the band-clamp into operating position when a boot is being jacked, means is provided for automatically releasing the bracket for downward movement when the post 91 is swung back into position to carry the boot into the band-clamp. The latching-member 69 has an upwardly projecting arm to which is pivoted a link 105 (Fig. 2). The forward end of the link 105 passes through a stud 107 projecting from an arm 109 pivoted on the plate 79. A nut and a lock-nut 111 are threaded on the link in front of the arm 109. Pivoted on the arm is a pawl 113 backed by a spring-plunger 115, which urges the pawl in a clockwise direction until a stop-face 116 on the pawl contacts with the arm 109. The pawl is arranged to lie over a hardened steel strip 117 on the arm 99 of the post 91, so that when the post is swung rearwardly into the machine to carry a boot into position to have a heel attached, the strip 117, acting through the pawl, will swing the

arm 109 in a direction to cause forward movement of the link 105. This will actuate the latching-member 69 to free the bracket 27, so it will be unnecessary for the operator to actuate the handle 87. As the roll 101 on the arm 99 reaches the top of the curved portion of the slot 103, the pawl 113 and the strip 117 will be separated. The arm 109 will then be again carried into a position such that when the post 91 is moved to its boot-receiving position, the pawl and strip will contact with one another in readiness for tripping the latch upon presentation of the next boot in operating position.

For closing the band-clamp about a shoe-upper 15 applied thereto, there are two cams 119 and 121 (Fig. 5) on a vertical cam-shaft 123 journaled in the supporting member 33. The cams are arranged to contact with rolls 125 and 127, respectively, mounted on the right operating arm 11 and on an extension 129 of the left arm 11. A spring 131 inter-connecting the arms serves to maintain the rolls in engagement with their cams. For rotating the cam-shaft to cause the band-clamp to close, said shaft has a transversely extending arm 133 secured thereon. A link 135 connects this arm to a second arm 137 fast upon a pin 139 rotatable upon the supporting member 33. Also secured to the pin 139 is a forwardly extending member 141 having a vertical pin 143 rotatable upon its forward end. Threaded through the pin 143 is a horizontal rod 145 which has a finger-piece 147 by which it may be rotated. The rod 145 is also threaded through a vertical pin 149 rotatable upon a forwardly extending arm of a bell-crank-lever 151 pivoted by a pin 153 rotatable in the bracket 27. The other arm of the bell-crank-lever is attached to a rearwardly extending rod 155 (Fig. 1), which normally holds said lever against rotation about its pivot. The screw-threads which pass through the pins 143 and 149 are right and left, so that by rotation of the rod 145, while the lever 151 is held stationary, the member 141 will be moved. This, through the arms 133 and 137 and link 135, will cause the rotation of the cams 119 and 121 to move the arms 11, 11 of the band-clamp away from each other or permit them to approach.

The rod 155, which is connected to the lever 151, is joined at its rear end to the upper end of the upwardly extending arm of a bell-crank-lever 157 pivoted on a stud 159 on the frame of the machine (Fig. 3). The lever 157 has a forwardly extending arm to which is pivotally connected the upper end of a rod 161, which at its lower end passes through the pivot-pin 163 of a lever 165, said pin being rotatable in the machine-frame. A spring 167, surrounding the rod 161 and confined between the lever 165 and a collar 169 fast on the rod, normally urges the lever 157 in such direction as to cause the rod 155 to move the band-clamp-arms 11, 11 toward each other. In order to hold the band-clamp latched open, when the machine is idle and the spring 167 in condition ready to move the band-clamp into shoe-upper-clamping position, the forward end of the lever 165 has pivoted to it an upwardly extending bar 171. To the upper end of the bar is secured a latch-plate 173 (Figs. 1 and 3), this latch-plate being adapted to contact with a wear-plate 175 on the forwardly extending arm of the lever 157. The rear end of the lever 165 is connected to a rod 177, the lower end of which is pivoted on the forward end of the clutch-throw-out lever 6, previously mentioned. A spring 179, connected as indicated below, tends to swing the bar 171

rearwardly of the machine, and with the parts in their normal positions, the latch-plate 173 is held in contact with the wear-plate 175 on the lever 157, so the spring 167 is maintained under compression with the band-clamp open.

For moving the latch-plate 173 to free the lever 157, so it may receive the action of the compressed spring 167, the bar 171 has pivoted thereon a pawl 181. A spring 179 connects a forwardly extending tail of the pawl to the frame of the machine, so that it tends to swing said pawl counterclockwise, as seen in Fig. 1, into contact with an angled face of a block 183 attached to a substantially horizontal rod 185. At the rear extremity the rod is guided upon the frame, while the forward end is pivoted to a member 187 secured to a rock-shaft 189, which is turned by a link 190 raised upon depression of the treadle 4. At this time, the rock-shaft is moved in a clockwise direction and the rod 185 is moved forward. The 10 rod carries in the same direction the block 183, which by engagement with the pawl 181 will swing the bar 171 to free the lever 157 from the latch-plate 173 for actuation by the compressed spring 167. The shaft 189 is rocked during the initial 15 part of the downward movement of the treadle and consequently early control of a shoe by the band-clamp is assured. Since its actual movement into shoe-engaging position is brought about under the action of the spring, the operator is relieved of the necessity of moving, through the treadle, the band-clamp itself. Therefore, the amount of energy expended by the operator is lessened.

It may occasionally happen that, due for example to the operator not presenting a shoe correctly to the machine, it is desirable to release the shoe after it has been gripped by the band-clamp and before the power-operation of the machine is started. For this purpose, the stud 153 by which the lever 151 is pivoted has also pivoted thereon a handle 191. The handle has a downwardly extending web 193 (Fig. 5) arranged to lie against an abutment-screw 195 threaded in an arm of the lever, so that upon rocking the handle 191 counterclockwise said lever may be moved to open the band-clamp. Simultaneously, the rod 155 will be moved forward to swing the lever 157 and compress the spring 167 once more. The latch-plate 173 is also caused to contact with the wear-plate 175 to hold the spring so compressed.

As described in the previously mentioned Patent No. 2,085,851, the machine may be used for spanking a top-lift on a heel after said heel has been attached to a shoe by the machine. It will be appreciated that if a heel only is to be attached, it is desirable to re-load the spring 167 before the end of the machine-operation and to open the band. But if the machine is to be used for spanking a top-lift onto a heel, the band-clamp should be prevented from opening to release the shoe upon the stopping of the machine between the heel-attaching and the top-lift-spanking cycles. Means has therefore been provided which may be caused to act, under the control of the operator, either to open the band-clamp and compress the spring 167 at the end of but one cycle of operation of the machine, when heel-attaching only is to be effected, or to cause opening of the band-clamp only after a second cycle of operation when a top-lift is to be spanked on an attached heel. This means comprises a bell-crank-lever 197 (Figs. 1 and 3) pivoted on the stud 159 and carrying a pin 199 on the forward

end of its forwardly extending arm. A block 201 is supported by the pin 199 and may be held in one of two positions relatively to the lever by a spring-plunger 203 on the lever engaging either 10 of two depressions on the block. In one of these positions, a roll 205 on the bar 171 lies against a downwardly and rearwardly sloping cam-face 207 on the block 201. In the other position, the cam-face 207 on the block is held away from the roll 205. As is common in heelers of the character of that now under consideration, the illustrative machine is provided with the swing-plate 209 (Fig. 1) carrying a heel-positioning device and a top-lift-positioning device. This swing-plate 15 is arranged, first to occupy such a position that a heel is presented over the support 1. Then, after the heel has been attached to the shoe, the swing-plate is shifted to such a position that a top-lift is presented underneath the already attached heel. For use in heel-attaching without top-lift-spanking, it is not necessary to cause the oscillation of the swing-plate, and, as above stated, after the heel-attaching operation, it is desirable to release the shoe from the band-clamp and to 20 recompress the spring 167. In the latter case, the block 201 is moved to the left (Fig. 3), so that its cam face 207 is held away from the roll 205. Then, when near the end of the power-operation of the machine, the clutch-throw-out lever 6 is moved to cause the machine to be stopped, the rod 177 is first moved down and then up to its 25 original position, in readiness for the next cycle of the machine. The downward movement of the rod 177 will cause the latch-plate 173 on the bar 171 to be moved up, so the spring 179 will carry the latch-plate over the wear-plate 175 on the lever 157. Thereafter, the upward movement of the rod 177 will cause the latch-plate 173 to move downwardly, moving the bell-crank-lever 157 with it, opening the band-clamp and re-compressing the spring 167, in readiness for the next 30 cycle of the machine.

When a top-lift is to be spanked on to an attached heel, however, the block 201 is moved to the right, so that the cam-face 207 thereon will contact with the roll 205 on the bar 171. Upon 35 actuation of the machine-treadle 4 of the lever 157 is released, through the movement of the block 183 to the right, to receive the action of the spring 167 and cause the band-clamp to close about the shoe upper. When near the end of the 40 machine-cycle the bar 171 with its latch-plate 173 is carried first up and then down, as a consequence of the movement of the rod 177 by the stop-lever 6, the roll 205 on the bar 171 will travel along the cam-face 207. Owing to the shape of the cam-face, the latch-plate will be prevented from engaging the wear-plate 175 on the lever 157. Therefore, when the power-cycle of the 45 machine is ended, the band-clamp will remain in engagement with the shoe-upper.

For the top-lift-spanking cycle of operations, the swing-plate 209 will be moved to carry a top-lift under the already attached heel, and, as seen 50 in Fig. 1, there is connected to the swing-plate a rock-arm 211. The rock-arm is joined to the forward end of a rod 213 connected at the rear to a downwardly extending arm of the bell-crank-lever 197 on which the block 201 is mounted. The 55 arrangement is such, that upon movement of the swing-plate to carry a top-lift into position under an attached heel on a shoe in the band-clamp, the arm 211 is similarly oscillated, and through the rod 213 causes the lever 197 to be moved in a counterclockwise direction. This movement of 60

the lever will carry the cam-face 207 on the block 201 away from the roll 205 on the bar 171. Therefore, when the bar receives its longitudinal movement near the end of the machine-cycle, the latch-plate 173 will be able, once more, to engage the wear-plate on the lever 157 and move that lever to open the band-clamp and compress the spring 167.

In using our improved machine for attaching a heel to a shoe and for spanking a top-lift on the attached heel, the post 91 will be in its vertical position and the nail-loading device will have been supplied with a load of nails. A heel and a top-lift will be placed in their respective positioning devices on the swing-plate 209. The operator will then cause movement of the nail-loading device over the support 1 to deliver a load of nails thereto, and, as the loading device is thus actuated, the cam-roll thereon will engage the cam-piece 65 and lift the band-clamp vertically away from the support 1. The catch 67 will engage the latch 69, thereby holding the band-clamp raised. The swing-plate will be moved so that a heel thereon will be position over the support and the counter-portion of a shoe-upper will be introduced into the band-clamp. While holding a shoe-upper in place with one hand, the operator will depress the handle 87 with his other hand to release the band-clamp mechanism for downward movement. After the band-clamp has reached its operating position, determined by engagement of the free end of an arm of the bell-crank-lever 77 with the boss 81 on the plate 79, the operator will depress the treadle 4. The first part of the depression of the treadle will cause rocking of the shaft 189. This lowers the last-plate 89 to press the shoe against the heel with preliminary pressure by rotation of the member 187, an upwardly extending rod 215 connected to the member effecting this. At the same time, the rod 185 will be moved forwardly to disengage the latch-plate 173 from the wear-plate 175, thereby allowing the compressed spring 167 to move the lever 157 in a counterclockwise direction as seen in Figs. 1 and 3. This movement of the lever will cause the band-clamp to close about the counter-portion of the shoe-upper. Further depression of the treadle will trip the clutch of the machine and initiate its power-operation. The plunger 97 will thereupon be lowered to cause the post 91 to press the shoe and heel more firmly together, and then the heel-attaching nails will be driven from the support 1 through the heel and into the shoe. The end portions of the nails are left projecting slightly from the bottom of the heel in preparation for the spanking of the top-lift on the heel. When near the end of the power-operation of the machine, the clutch-throw-out lever 6 moves the rod 171 first down and then up, and the latch-plate 173 will be moved by the bar 171, but owing to the cam-face 207 on the block 201 engaged by the roll 205 on the bar, the latch-plate will be prevented from contacting with the wear-plate 175 and opening the band-clamp. As the machine comes to rest, the post 91 will be moved up to relieve the pressure on the shoe. The swing-plate 209 will then be shifted to carry a top-lift underneath the attached heel, and this movement will cause the lever 197 to be swung in such a direction that the cam-face 207 will be carried away from the roll 205 on the bar 171. The band-clamp therefore remains closed. The operator will then depress the treadle a second time, and pressure will be applied by the plunger 97 to cause the top-lift to be impaled on the projecting

ends of the nails. As the power-operation of the machine nears its completion, the latch-plate 173 will not be prevented from engaging the wear-plate 175 owing to the disposition of the block 201.

5 Engagement of the latch-plate with the wear-plate will move the lever 157 in a clockwise direction, as seen in Figs. 1 and 3, to cause opening of the band-clamp, and re-compression of the spring 167 in readiness for operation on the next shoe.

10 Having described the invention, what we claim as new and desire to secure by Letters Patent of the United States is:

1. In a heel-attaching machine, fastening-inserting mechanism, means for engaging the counter-portion of a shoe to locate it for the insertion of the fastenings, said engaging means being movable to receive and release a shoe or to clamp it for the inserting operation, and means made effective under the power of the machine for moving the shoe-engaging means.

15 2. In a heel-attaching machine, fastening-inserting mechanism, means for engaging the counter-portion of a shoe to locate it for the insertion of the fastenings, said engaging means being movable into open or closed relation,

20 25 means for closing the engaging means, and means movable under the power of the machine for opening the engaging means and rendering the closing means effective.

30 3. In a heel-attaching machine, fastening-inserting mechanism, means for engaging the counter-portion of a shoe to locate it for the insertion of the fastenings, said engaging means being movable into open or closed relation,

35 35 means for closing the engaging means, means movable under the power of the machine for opening the engaging means and rendering the closing means effective, means for temporarily retaining the engaging means in its open position, and means movable by the operator to release the engaging means for closure.

40 4. In a heel-attaching machine, fastening-inserting mechanism, means for engaging the counter-portion of a shoe to locate it for the insertion of the fastenings, said engaging means being movable to receive and release a shoe or to clamp it for the inserting operation, a member

45 50 movable upon starting the operation of the machine, a member movable upon stopping the operation of the machine, means controlled by the starting member for moving the engaging means to clamp the shoe, and means controlled by the stopping member for moving the engaging means to release the shoe and to prepare for the clamping of another.

55 5. In a heel-attaching machine, fastening-inserting mechanism and pressing mechanism acting in successive cycles to perform a plurality of operations upon a shoe, means for engaging the counter-portion of a shoe to locate it for such operations, means made effective under the power of the machine for moving the shoe-engaging means, and means for preventing the movement

60 65 of the shoe-engaging means between the successive cycles.

6. In a heel-attaching machine, fastening-inserting mechanism and pressing mechanism acting in successive cycles to perform a plurality of operations upon a shoe, means for engaging the counter-portion of a shoe to locate it for such operations, a member movable upon starting an operating cycle of the machine, a member movable upon stopping such operation, means controlled by the starting member to move the en-

gaging means to clamp the shoe, means controlled by the stopping member to move the engaging means to release the shoe and to prepare for the clamping of another, and means for preventing the action of the stopping member upon the engaging means between successive cycles.

7. In a heel-attaching machine, a band-clamp provided with movable arms, and means made effective under the power which produces an operating cycle of the machine to move the arms.

8. In a heel-attaching machine, a band-clamp provided with movable arms, and means made effective under the power which produces an operating cycle of the machine to move the arms relatively to each other.

9. In a heel-attaching machine, a band-clamp provided with movable arms, means made effective under the power of the machine to move the arms, and means arranged to be set by the operator for preventing such movement of the arms.

10. In a heel-attaching machine, a band-clamp provided with movable arms, means acting under the power of the machine for separating the arms, and means prepared for operation under the power of the machine for closing the arms to clamp the work.

11. In a heel-attaching machine, a band-clamp provided with movable arms, a spring acting to close the arms, a member movable under the power of the machine to load the spring, and means arranged to move the member to release the spring for its action upon the band-clamp.

12. In a heel-attaching machine, a band-clamp provided with movable arms, a spring acting to close the arms, a member movable under the power of the machine to load the spring, and a plurality of independently operable means arranged to move the member to release the spring for its action upon the band-clamp.

13. In a heel-attaching machine, a band-clamp provided with movable arms, a lever movable to open and close the arms, a spring acting upon the lever to close the arms, a movable latching member engaging the lever to hold the arms open against the force of the spring, means for moving the member to load the spring, and means for moving said member to release the lever and permit the spring to act.

14. In a heel-attaching machine having a starting member and a stopping member, a band-clamp provided with movable arms, a lever movable to open and close the arms, a spring acting upon the lever to close the arms, a movable latching member engaging the lever to hold the arms open against the force of the spring, means connected to the stopping member for moving the latching member to load the spring, and means connected to the starting member for moving said latching member to release the lever and permit the spring to act.

15. In a heel-attaching machine having a starting member and a stopping member, a band-clamp provided with movable arms, a lever movable to open and close the arms, a spring acting upon the lever to close the arms, a movable latching member engaging the lever to hold the arms open against the force of the spring, means connected to the stopping member for moving the latching member and thereby the lever to open the arms and load the spring, means connected to the starting member for moving the latching member to release the lever and permit the spring to act, and means arranged for movement by the operator to either permit or prevent the movement of the lever by the latching member.

16. In a heel-attaching machine, a band-clamp provided with movable arms, a lever movable to open and close the arms, a spring acting upon the lever to close the arms, a movable latching member engaging the lever to hold the arms open against the force of the spring, means for moving the member to load the spring, means for moving said member to release the lever and permit the spring to act, and means for preventing the return of the member from its releasing to its spring-loading position.

17. In a heel-attaching machine, a band-clamp provided with movable arms, a lever movable to open and close the arms, a spring acting upon the lever to close the arms, a movable latching member engaging the lever to hold the arms open against the force of the spring, means for moving the member to load the spring, means for moving said member to release the lever and permit the spring to act, and means for preventing the return of the member from its releasing to its spring-loading position.

18. In a heel-attaching machine, a band-clamp provided with movable arms, a lever movable to open and close the arms, a spring acting upon the lever to close the arms, a movable latching member engaging the lever to hold the arms open against the force of the spring, means for moving the member to load the spring, means for moving said member to release the lever and permit the spring to act, and a member arranged to be set by the operator to either permit or prevent the return of the member from its releasing to its spring-loading position.

19. In a band-clamp, a support having a transverse guideway, a slide movable along the guideway, a shoe-engaging band carried by the slide, a lever fulcrumed upon the slide, and a link joining the lever to the support.

20. In a band-clamp, a support having a transverse guideway, a slide movable along the guideway, a shoe-engaging band carried by the slide, a lever fulcrumed upon the slide, a link joining the lever to the support, and means for variably limiting the extent of movement of the lever.

21. In a band-clamp, a support having a transverse guideway, a slide movable along the guideway, a shoe-engaging band carried by the slide, a lever fulcrumed upon the slide, a link joining the lever to the support, and stop-screws threaded through the lever arranged for engagement with the support.

22. In a band-clamp, a bracket provided with a forwardly extending guideway having longitudinally extending rack-teeth, a support movable along the bracket-guideway and having a transverse guideway, a pinion rotatable upon the support and meshing with the rack-teeth, a slide movable along the support-guideway, a shoe-engaging band carried by the slide, a lever fulcrumed upon the slide, and a link joining the lever to the support.

23. In a band-clamp, a fixture, a bracket movable vertically upon the fixture, means through which the bracket may be elevated upon the fixture, a shoe-engaging band carried by the bracket, a catch pivoted upon the bracket, a latch mounted upon the fixture for engagement with the catch when the bracket is elevated, and a member connected to the catch and movable by the operator to release the bracket.

24. In a band-clamp, a fixture, a bracket movable vertically upon the fixture, means through which the bracket may be elevated upon the fix-

ture, a shoe-engaging band carried by the bracket, a catch pivoted upon the bracket, a latch mounted upon the fixture for engagement with the catch when the bracket is elevated, a member connected to the catch and movable by the operator to release the bracket, and means arranged to limit variably the descent of the bracket.

25. In a band-clamp, a fixture, a bracket movable vertically upon the fixture, a cam mounted upon the bracket and through which it may be elevated upon the fixture, a shoe-engaging band carried by the bracket, means for temporarily retaining the bracket in its elevated relation, means movable by the operator to release the bracket from the retaining means, means arranged to limit the descent of the bracket, and means acting upon the movement-limiting means for cushioning the descent of the bracket.

26. In a heel-attaching machine, a frame, a pressure-plunger movable thereon, a bracket movable vertically upon the frame, a shoe-engaging band carried by the bracket, means for temporarily retaining the bracket in a raised position, a jack movable upon the plunger, and means connecting the jack to the retaining means whereby said retaining means is moved to release the bracket upon movement of the jack.

27. In a heel-attaching machine, a frame, a pressure-plunger movable thereon, a bracket movable vertically upon the frame, a shoe-engaging band carried by the bracket, means for temporarily retaining the bracket in a raised position, a stop-lever fulcrumed upon the pressure-plunger, and means connecting the stop-lever and bracket whereby said stop-lever limits the descent of the bracket.

28. In a heel-attaching machine, a frame, a pressure-plunger movable thereon, a bracket movable vertically upon the frame, a shoe-engaging band carried by the bracket, means for temporarily retaining the bracket in a raised position, a stop-lever fulcrumed upon the pressure-plunger, and a link variable in length and connecting the stop-lever and bracket.

29. In a heel-attaching machine, a frame, a pressure-plunger movable thereon, a bracket movable vertically upon the frame, a shoe-engaging band carried by the bracket, means for temporarily retaining the bracket in a raised position, a stop-lever fulcrumed upon the pressure-plunger, and a spring acting upon the stop-lever to cushion the descent of the bracket.

THOMAS AUBREY KESTELL.
